COMPRESSOR CONTROLLING MECHANISM

Original Filed June 15, 1920

Patented Nov. 6, 1923.

1,473,078

UNITED STATES PATENT OFFICE.

LEWIS J. CLAPP, OF CLAREMONT, NEW HAMPSHIRE, ASSIGNEE TO SULLIVAN MACHINERY COMPANY, A CORPORATION OF MASSACHUSETTS.

COMPRESSOR-CONTROLLING MECHANISM.

Application filed June 15, 1920, Serial No. 389,197. Renewed January 31, 1928.

To all whom it may concern:

Be it known that I, LEWIS J. CLAPP, a citizen of the United States, residing at Claremont, in the county of Sullivan and State of New Hampshire, have invented certain new and useful Improvements in Compressor-Controlling Mechanisms, of which the following is a full, clear, and exact specification.

10 My invention relates to compressor controlling mechanisms.

An object of my invention is to provide an improved compressor controlling mechanism. Another object of my invention is 15 to provide an improved compressor controlling mechanism which shall control both the running of the compressor and its condition whether loaded or unloaded. Other objects of my invention will appear in the 20 course of the following specification and claims.

In the accompanying drawings I have shown for purposes of illustration, one form which my invention may assume in practice.

25 In these drawings,—

Fig. 1 is a side elevation of a compressor plant embodying my improved controlling mechanism and showing parts broken away to illustrate details of construction.

30 Fig. 2 is a central longitudinal vertical section through my improved compressor controlling mechanism proper.

Fig. 3 is a fragmentary detail of the electric control mechanism.

35 For purposes of illustration I have shown my improved controlling mechanism applied to a compressor which is generally indicated by 1 and which is driven by a motor 2, the latter being supplied with 40 electric current from mains 3 and 4 under control of a main switch 5. The main switch 5 is controlled by a pilot switch 6 (see Figs. 2 and 3) which is of well known construction and in which the circuit controlled by the switch is opened and closed 45 respectively by the application of pressure to and the removal of pressure from the operating pin 7. The details of construction of this switch are well known and further 50 description is accordingly considered unnecessary. It will be obvious that when the circuit controlled by the switch 6 is opened the solenoid 8 which operates to cause the closing of the main circuit through the 55 motor will be without current and accord-

ingly the main circuit will be opened and the motor stopped. The discharge chest 9 of the compressor is connected by means of a pipe 10 with a receiver 11 which in turn is connected by way of a pipe 12 with 60 a Judson pilot valve of well known construction, the pilot valve being of that type which upon rise in receiver pressure above the desired limit operates to admit a flow of receiver pressure through the pilot valve 65 and, upon a drop of the pressure to a pre-determined degree, to cause a closure of the communication opened through the pilot valve and the opening of an exhaust. This pilot valve is designated by 13 and its exhaust is indicated at 14, this exhaust being open at such time as the pilot valve is closed. The compressor is provided with 70 inlet valve mechanism of well known type comprising valve members 15 (of which but 75 one is shown) adapted to be opened by suction within the compressor cylinder and normally yieldingly held closed by a spring 16. Cooperating with a stem 17 formed on the valve 15 is a plunger 18 which is adapted 80 to be raised by air transmitted by the pipe 19 and when so raised to open and so maintain, during the continuance of the air pressure supply, the inlet valves 15, thereby 85 permitting the air on opposite sides of the compressor piston to surge back and forth without the further pumping of air into the receiver.

My improved controlling mechanism, 90 which is generally indicated by 20, comprises means for supplying air to the plungers 18 and preventing escape therefrom prior to the moment when the compressor driving motor 2 has brought the compressor up to speed, and means for controlling the 95 switch 6 whereby the compressor driving motor may be stopped and started in a desired manner. The member 20 is provided with a cylindrical bore 21 with which the pilot valve communicates by way of a passage 33 and within which there is reciprocable a piston 22 provided with suitable packing means 23 and normally retained at the right hand end of the cylinder 21 by means of a spring 24. The piston is provided with an adjustable plunger pin 25 which is adapted to contact with the pin 7 when the piston is adjacent the left hand end of the cylinder and thereby cause the 100 opening of the switch 6 and the resultant 105 opening of the switch 6 and the resultant 110

opening of the main circuit through the motor 2. Located at the right hand end of the cylinder 21 and arranged within a cylinder closure member 26 is a valve 27 slidably mounted in a chamber 28 and having a pin 29 adapted to be engaged by the piston 22 when the latter is at the right hand end of its travel. When the piston 22 is in right hand position, the valve 27 stands open, 10 being moved from its seat 30 and air may pass, on opening of valve 13, by way of the port 31 surrounding the stem 29 to the chamber 28 and thence by way of a pipe 32 through the pipes 19, thus resulting in an 15 opening of the valves 15. The valve 27 is normally closed by a spring 27'.

The operation of the mechanism described is as follows:

Let it be assumed that the compressor 1 is 20 being driven by the motor 2 and that the pressure in the receiver 11 rises above a predetermined height. When this occurs, the pilot valve 13 is operated to close the exhaust 14 in a well known manner and to 25 transmit pressure to the cylinder 21 by way of the connection 33. Prior to this time the valve 27 has been maintained open by the pressure of the piston 22 against the stem 29, but upon movement of the piston 22 to 30 the left, the valve 27 will at once close. Prior to this event, however, pressure will be transmitted between the head of the piston 22 and the member 26 and through port 31, chamber 28, and pipes 32 and 19 to act 35 upon the lower sides of the piston members 18 to open the inlet valves. As soon as the pressure of the piston 22 is removed from the stem 29, the valve 27 closes and entraps the pressure within the pipes 32 and 19 and 40 beneath the plungers 18. When the piston 22 approaches its left hand limit of travel it throws the switch 6, opening the circuit therethrough and so opening the main circuit through the motor 2 causing resultant 45 stopping of the latter. When the pressure within the receiver 11, due to the use of air therefrom, drops too low, the pilot valve 13 operates to cut off the supply of air to the chamber 21 and open communication between the latter and the exhaust port which 50 is preferably of relatively small size. The piston at once begins to move to the right hand end of its cylinder under the influence of the spring 24 and a very slight movement 55 of the piston will permit the closing of the switch 6 and the resultant starting of the motor. Prior to the time when the piston 22 reaches a point where it will contact with the member 29, the motor will have brought 60 the compressor up to full speed, and so the exhaust of air beneath the plunger 18 which will take place when the opening of the valve 27 by the piston 22 brings the pipes 19 and 32 in communication with the 65 exhaust port 14, will cause a reloading of the

compressor only after the compressor is up to speed. If, during the time that the receiver pressure remains high enough to cause the pilot valve to remain open, leakage should occur from the pipes 32 and 19, or around the plungers 18, the valve 27 will be momentarily opened by the pressure within the cylinder 21 and accordingly the pressure beneath the pistons 18 will be maintained sufficient to cause the compressor to 75 remain unloaded.

While I have in this application specifically described one form which my invention may assume in practice, it will be understood that this form of the same is shown 80 for purposes of illustration and that the invention may be modified and embodied in other forms without departing from its spirit or the scope of the appended claims.

What I claim as new and desire to secure 85 by Letters Patent is:

1. The combination with a compressor and a driving motor therefor, of controlling means for said compressor and for said motor comprising a cylinder, a piston therein, a plunger on said piston, means in alignment with said plunger and engageable thereby for controlling said motor, and means coaxially arranged with said piston and controlling the condition of said compressor. 95

2. The combination with a compressor, a driving motor therefor, and a receiver, of controlling means for said compressor and for said motor comprising a cylinder, a piston therein, means normally disposing said piston in one end of said cylinder, means responsive to receiver pressure to supply and exhaust fluid to and from said cylinder, means in alignment with said piston for controlling said motor, and means coaxially arranged with said piston for controlling the loading of said compressor and controlled by said piston when the latter is adjacent the end of said cylinder toward which it is disposed by said second mentioned means. 100

3. The combination with a compressor, a driving motor therefor, and a receiver, of controlling means for said compressor and for said motor comprising a cylinder, a piston therein, means responsive to receiver pressure to supply and exhaust fluid to and from said cylinder, means in alignment with said piston for controlling said motor, and means coaxially arranged with and adapted to be controlled by said piston for controlling the loading of said compressor said last mentioned means being disposed at the opposite side of said piston from said motor 110 controlling means. 115

4. The combination with a compressor, a driving motor therefor, and a receiver, of controlling means for said compressor and for said motor comprising a cylinder, a 120

piston therein, means responsive to receiver pressure to supply and exhaust fluid from said cylinder, means in alinement with said piston for controlling said motor, and means 5 coaxially arranged with said piston and adapted to be impacted thereby for controlling the condition of said compressor, said last mentioned means being disposed at the opposite side of said piston from said 10 motor controlling means.

5. The combination with a compressor, a driving motor therefor, unloading means for said compressor, controlling means for said driving motor, and a receiver, of controlling mechanism for said compressor unloading means and motor controlling means comprising means subjected on one side to the action of a spring, means for subjecting the opposite side of said third 15 mentioned means to receiver pressure or to atmospheric pressure depending upon the receiver pressure, and means on opposite sides of said third mentioned means and controlled thereby for controlling said unloading and motor controlling means.

6. The combination with a compressor, a driving motor therefor, and a receiver, of controlling means for the compressor and for the motor comprising a cylinder, a piston 20 ton therein, means responsive to receiver pressure for alternately supplying receiver pressure to said cylinder and exhausting it therefrom, and a valve adapted to be opened by said piston when the latter is at one end 25 of its travel and when so open to permit the flow of fluid pressure to or from said compressor controlling means, through said cylinder.

7. The combination with a compressor, a 30 driving motor therefor, and a receiver, of controlling means for said compressor and for said motor comprising a cylinder, a piston therein, means responsive to receiver pressure for supplying fluid pressure to said cylinder or exhausting it therefrom, means adapted to be actuated by said piston to control said motor, and a valve controlling said compressor controlling means and normally held open by said piston to admit 35 a supply of fluid pressure to said compressor 40 unloading means from said cylinder and to discharge the same therefrom and having means to close it upon movement of said piston upon admission of fluid pressure to said cylinder.

8. The combination with a compressor and a driving motor therefor, of controlling means for said compressor and for said motor comprising a stationary member, a 45 movable member therein, and movable elements disposed at opposite sides of said movable member and operable thereby for effecting control respectively of said driving motor and of said compressor.

9. The combination with a compressor and a driving motor therefor, of controlling means for said compressor governing the loading and unloading thereof and for said motor governing the starting and stopping thereof including relatively movable cylinder and piston elements, and means engageable by the opposite ends of the movable one of said elements respectively controlling loading and unloading of the compressor and starting and stopping of the motor.

10. The combination with a compressor and a driving motor therefor, of controlling means for said compressor governing the loading and unloading thereof and for said motor governing the starting and stopping thereof including a stationary cylinder and a piston movable therein, and means engageable by opposite ends of said piston respectively controlling the loading and unloading of the compressor and the starting and stopping of the motor.

11. In a compressor system, a compressor, a driving motor therefor, a control switch therefor, unloading means for said compressor including a discharge pressure responsive valve, mechanism controlled thereby operative on supply of fluid to unload the compressor and a connection between said valve and mechanism including a one-way check valve opening toward said mechanism, and means controlled by said compressor discharge pressure responsive valve including a member movable in one direction to effect operation of said control switch and in the opposite direction to open said check valve.

12. In a compressor system, a compressor, driving means therefor, pressure operated compressor loading and unloading means, a fluid supply and discharge connection leading thereto, and means for controlling said driving means and said loading and unloading means including a cylinder, a piston in said cylinder, an element adapted to be actuated by said piston to interrupt the driving of said compressor by said driving means, compressor discharge pressure responsive means controlling the movements of said piston and controlling the supply and discharge of fluid pressure to said connection to said compressor loading and unloading means, and a supplemental controlling means in said connection mechanically controlled by said piston.

13. In a compressor system comprising a compressor and means for driving the same, means for stopping and starting the compressor in accordance with variations in discharge line pressure and for causing said compressor to be started unloaded and to be loaded when a predetermined speed of drive is reached comprising a member movable in opposite directions when compressor discharge pressure respectively exceeds and falls below a predetermined amount, means

for controlling the compressor driving means adapted to be actuated by said member adjacent one end of its path of movement, and a valve adapted to be moved to open position and controlling the loading of the compressor arranged to be opened as said member approaches the opposite end of its movement.

14. In a compressor system comprising a compressor and means for driving the same, means for stopping and starting the compressor in accordance with variations in discharge line pressure and for causing said compressor to be started unloaded and to be loaded when a predetermined speed of drive is reached comprising a member movable in opposite directions when compressor discharge pressure respectively exceeds and falls below a predetermined amount, means for controlling the compressor driving means adapted to be actuated by said member adjacent one end of its path of movement, a valve adapted to be moved to open position and controlling the loading of the compressor arranged to be opened as said member approaches the opposite end of its movement, and means for rendering the last mentioned movement of said member slower than its first mentioned movement.
15. In a compressor system comprising a compressor and means for driving the same, means for stopping and starting the compressor in accordance with variations in discharge line pressure and for causing said

compressor to be started unloaded and to be loaded when a predetermined speed of drive is reached comprising a member movable in opposite directions when compressor discharge pressure respectively exceeds and falls below a predetermined amount, means including a switch for controlling the compressor driving means adapted to be actuated by said member adjacent one end of its path of movement, and a valve adapted to be moved to open position and controlling the loading of the compressor arranged to be opened as said member approaches the opposite end of its movement.

16. In a compressor system comprising a compressor and means for driving the same, means for controlling the driving of said compressor by said driving means, fluid pressure means for loading and unloading said compressor comprising a compressor discharge pressure controlled pilot valve, means movable in opposite directions upon opening and closing of said pilot valve, means for controlling the operation of said motor actuated by said last mentioned means on one movement thereof, and means including a valve controlling the flow of fluid pressure which controls operation of said unloading means actuated by said fourth mentioned means on opposite movement of the latter.

In testimony whereof I affix my signature.

LEWIS J. CLAPP.
